UNITED STATES PATENT OFFICE.

FREDERICK CLIFTON MCLEAN AND JOHN PICARD, OF HAMILTON, NEW ZEALAND.

RAILWAY RAIL.

Application filed September 10, 1926, Serial No. 134,666, and in New Zealand July 27, 1926.

This invention relates to the rails used generally in the construction of railway tracks and it has been devised with the object of providing a special construction of rail, embodying therewith a system of joining with the next rails, that may displace the present form of square ended and butt joined rails, with the many disadvantages relating thereto. These disadvantages are concerned with the need for the use of fish plates in effecting a joint, and the constant care and attention necessary to keep them tight, and more especially are concerned with the difficulty in maintaining the two rail ends at a uniform level and with the break caused in the continuity of the running surface which leads to discomfort, bumping, and noise in the travel of the rolling stock upon the line.

In the present invention each rail is made of cross sectional shape so that the rail head tapers in width from the middle of the rail out to each end both tapers being on the same side of the head so that the other side is uniformly flat. These rails are adapted to be laid so that each rail for half its length overlaps the next rail, the uniform edges of the two rails being disposed on respectively opposite sides and the tapered edges being so made that all through the lengths of the rails a uniform width of rail head is formed.

Each rail is so constructed as to its flange portion that the flanges on the engaging faces between the overlapping ends are made to transversely overlap while the flanges on the respective outer sides are made of the ordinary full width in order thus to obtain a firm base for the rails when resting on the sleepers.

The overlapping rail ends are secured directly together by means of bolts passing transversely through them and in the fitting of which provision is made for the usual expansion and contraction of the rails.

The invention is illustrated in the accompanying drawings, in which:—

Figure 1 is a plan of one of the rails.

Figure 2 is a plan of a number of the rails laid end to end and joined in accordance with this invention.

Figure 3 is a side elevation, on an enlarged scale of the joining ends of the rail.

Figure 4 is an enlarged cross sectional elevation on the line 4—4 of Figure 2.

Figure 5 is a similar cross sectional elevation on the line 5—5 of Figure 2.

The rail, as shown, is formed with the usual head A, the stem B, and flange C, but in this invention the said flange extends only on one side of the rail, while on the other side its place is taken by a narrow ledge D which may be disposed on the level of the rail flange base or elevated to a level just above the level of a low level ledge to provide for one ledge resting on the other when two ledges thus disposed are arranged to overlap.

The head A, in this invention, is on one side of the stem B made with a uniform side face, but on the other side, and the side corresponding with that on which the ledge D extends, is made to incline laterally inward, from the middle of the rail out to each end thereof, so that the rail head from its maximum width at the middle, tapers off to a fine edge at each end, where its width is made uniform with the thickness of the stem, the thickness of which is correspondingly tapered. The said maximum and minimum widths of the rail head are made to aggregate a full normal width of rail head. The surface of the tapered extremity also is made slightly lower than the rest.

A rail thus made is therefore adapted to be arranged in line with two other rails similarly made so that its head is overlapped from both ends to the middle by the respective halves of the other two rails when such other rails have the sides reversed relatively to the middle rail. This manner of arranging the rails is shown in the drawings and provides that a rail tread is formed continuously of uniform width and made up of the overlapping halves of the rail lengths so that the running surface for the wheels of the rolling stock is made continuous and without break.

When also the rails used are alternately made with the raised and low ledges D, the overlapping half lengths of the rails will have their ledges D also transversely overlapping, to sustain one upon the other, and thereby with the respective flanges C to provide a firm and level support for the rails upon the sleepers to which they are secured in the usual way.

The overlapped rail ends are secured together by means of the bolts E passing trans-

versely through their stems B, and positioned near each rail end. The holes in the end through which the bolts pass may be slotted in the usual way to allow for the expansion and contraction of the rails, and for the same purpose, a small space will be left between the adjacent ends of the overlapping halves, as at F in Figure 2, where however the relative space allowed is somewhat exaggerated.

To stay the two stems of the overlapped rails against distortion through the screwing of the bolts E, and to keep both parts of the joint plumb, a distance piece G (Figure 4) may be formed on the inside face of the rail stem, near its end, and which piece then engages the stem of the overlapped rail and keeps them uniformly plumb.

It will be seen that a track made up of these rails may be laid, each line of the track being formed by rails disposed so that the rails have their flanges C alternately on the outside and inside, and the ledges D alternately raised and low, and the rails are arranged to overlap each other in turn for half their length.

We claim:—

1. A railway rail having a head and a stem, said head being shaped to taper from a maximum width at the middle of the rail, outwardly to a minimum width at each end thereof, and having distance pieces formed on the inside face of the stem thereof.

2. A railway rail having a head and a stem, said head being shaped to taper from a maximum width at the middle of the rail, outwardly to a minimum width at each end thereof, and having a distance piece formed on the inside face of the stem near each end of the rail.

3. A railway rail having a head and a bottom flange, said head being shaped to taper from a maximum width at the middle of the rail outwardly to a minimum width at each

end thereof, the upper surface of the head at each end of the rail being tapered downwardly toward said flange.

4. A railway rail having a head and a stem, said head being shaped to taper laterally from a maximum width at the middle of the rail outwardly to a minimum width at each end thereof, and having a base flange on one side and a ledge projecting laterally from the other side at a level above that of the flange, and upon the side of the rail corresponding to that upon which the head edge is laterally tapered.

5. A railway line constructed of a plurality of rails formed as in claim 1, certain of said rails having a base flange on one side, and a ledge projecting laterally from the side, corresponding to that upon which the head edge is laterally tapered, at a level above that of the flange, and others of said rails having a base flange on one side and a ledge projecting laterally from the other side at the same level as said flange.

6. A railway line constructed of a plurality of rails formed as in claim 1, certain of said rails having a base flange on one side, and a ledge projecting laterally from the side, corresponding to that upon which the head edge is laterally tapered, at a level above that of the flange, and others of said rails having a base flange on one side and a ledge projecting laterally from the other side at the same level as said flange, said rails being arranged relatively so that each rail overlaps the next rail for half its length, and having the laterally tapered portions of their respective heads in contact, and having their respective ledges overlapping along the transverse direction of the rails.

In testimony whereof we affix our signatures.

FREDERICK CLIFTON McLEAN.
JOHN PICARD.
